DESIGN FOR A PACKAGE FOR SOAP POWDER OR SIMILAR COMMODITY

Neil H. Whitlock, Toledo, Ohio

Application December 12, 1945, Serial No. 124,665

Term of patent 14 years

(Cl. D58—12)

To all whom it may concern:

Be it known that I, Neil H. Whitlock, a citizen of the United States, residing at Toledo, in the county of Lucas and State of Ohio, have invented a new, original, and ornamental Design for a Package for Soap Powder or Similar Commodity, of which the following is a specification, reference being had to the accompanying drawing, forming a part thereof.

In the drawing:

Fig. I is a perspective view of a package for soap powder or similar commodity, showing my new design;

Fig. II is a similar perspective view of the opposite side and end;

Fig. III is a plan view of the unfolded box blank.

I claim:

The ornamental design for a package for soap powder or similar commodity, as shown.

NEIL H. WHITLOCK.
